VIRGIL L. GIBSON, OF SALEM, OREGON.

DRAWBAR SHIFT FOR TRACTORS.

Application filed March 8, 1927. Serial No. 173,745.

This invention relates to a draw bar shift for tractors.

An object of the invention is the provision of a device for easy and ready manipulation of the draw bar of the tractor at any time particularly while the tractor is in motion and under full load.

A further object of the invention is the provision of a swinging draw bar which is adapted to be manually shifted particularly when the tractor is plowing on a hillside and turning the furrow down the hill.

At this time the tractor and plow are both inclined to work down the hill and the plow does not provide a sufficient depth of cut. When the end of the field is reached it is necessary to turn the tractor so that the furrow is thrown up the hill whereby the plow will not cut too deeply. In shifting the swinging draw bar of my improved device I am able to overcome this difficulty by shifting the draw bar at a predetermined angle to the longitudinal axis of the tractor and maintaining the angular shift.

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a side view in elevation of a tractor equipped with the swinging draw bar and showing the means for operating the same.

Figure 2 is a horizontal section taken along the line 2—2 of Figure 1.

Figure 3 is a transverse vertical section taken along the line 3—3 of Figure 1.

Figure 4 is a fragmentary plan view of the rear end of the tractor.

Figure 5 is a view in perspective showing the rear end of a tractor and the operating means for shifting the draw bar, and

Figure 6 is a view in perspective showing the parts of the draw bar shifting device in detached relation.

Referring more particularly to the drawings 10 designates generally a tractor having a rear axle housing 11, a crank case 12 and a front axle 13.

A draw bar 14 is pivotally mounted at its inner end on a bolt 15 carried by the end of an arm 16 in a bracket 17 bolted to the inner end of the arm 16. A U-shaped bracket 18 is rigidly secured to the inner end of the arm 16 and to its upper face and is connected by means of a radius rod bolt 19 which is carried by a pair of ears 20 depending from the lower face of the crank case 12. The outer end of the bar 16 is bolted, as at 21, to the front end of the tractor frame and on the front axle bolt.

The free end of the draw bar 14 has an eye 22 pivotally connected thereto, as shown at 23. This free end of the arm is located between the arms 24 of the U-shaped cross head 25. This cross head is provided with passages 26 to receive the reduced ends 27 of a sleeve 28. The sleeve in conjunction with the reduced end 27 provides shoulders 29 which are adapted to abut the inner faces of the arms 24 of the cross head. The reduced portions are provided with diametrically disposed lugs 30 received by notches 31 formed in the arms 24 and opening into the passages 26. The co-operation of the lugs with the notches prevent rotation of the sleeve. Said sleeve is internally threaded, as shown at 32, for a purpose which will be presently described. A pair of brackets 33 are bolted to the differential casing 34 by means of the usual bolts 35 which secure the rear axle housings 11 to the differential casing. The outer ends of the brackets are provided with bearings 36 which receive a sleeve 37 and set screws 38 carried by the bearings secure the sleeve against rotation. A shaft 39 is rotatably mounted in the sleeve 37 and has a hand wheel 40 to provide for manual rotation of the shaft. A sprocket wheel 41 is rigid with an end of the shaft over which is trained a chain 42 adapted to drive the sprocket 43 rigid with one end of a screw 44.

At the upper end of depending brackets 45 are formed bearings 46 which are secured by set screws 47 to the sleeve 37. The lower ends of these brackets are provided with horizontal extensions 48 to which are secured bearings 49 formed of strap iron. A bolt 50 secures the bearing 49 to not only the horizontal extension 48 but to an inwardly extending flange 51 of the U-shaped bracket 52. This bracket is disposed inwardly of the cross head 25 since the bearings 49 project outwardly of the bracket where they re-

ceive the ends of the screw 44. This screw engages the threads 32 of the sleeve 28 so that when the screw is rotated the sleeve will be shifted towards the right or left, depending upon the direction of rotation of the screw and the shaft 39.

By loosening the set screws 47 the position of the brackets 45 may be varied so that they may be swung inwardly or outwardly of the rear ends of the tractor in order to properly position the cross head 25 in order to neatly receive the free end of the draw bar 14.

While I have particularly shown the draw bar for adaptation to a Fordson tractor it will be appreciated that minor changes may be made in its construction which will permit application of the shifting means for the draw bar to other types of tractors without changing the scope of the invention.

The pull of the tractor in the present device is maintained entirely upon the swinging draw bar and this pull in no way affects the shifting mechanism, thus eliminating all friction or pulling strain on said mechanism. When the tractor and plow are in motion a shift is made with only the slightest effort and it will be noted that the wheel for causing the shift operates with much more facility than the steering wheel of an automobile.

It will be noted that as the tractor and plow move from a level strip of land across a field where the land slopes more to the right so that the furrow is being turned down the hill the rear end of the tractor will tend to move down the hill, with the lower rear wheel moving farther away from the wall of the furrow as the grade increases. It is possible to maintain the front end of the tractor at the proper place by means of the steering wheel. However, the rear wheels tend to move down the hill due to the pulling strain upon them and there is always a slight slipping of the rear wheels due to the pull. The plow, however, has little tendency to move with the tractor down the hill as the side draft against the mold-boards tends to retain the plow in position.

When the rear end of the tractor begins to move down hill the rear end of the draw bar will not tend to move downwardly if it were allowed to freely swing at the rear end. As has been stated the plow will not tend to move down the hill due to the slight resistance as the plow is moving through the soil and it is this resistance that must be overcome to maintain the rear end of the draw bar in its proper place.

In order to maintain the shift properly the hand wheel is rotated and the shaft 39 is revolved as is the sprocket 41. Said sprocket drives a chain which in turn drives the sprocket 43 and causes rotation of the

screw 44. Since the screw has a threaded engagement with the sleeve 38 and the sleeve is maintained against rotation said sleeve is shifted either to the right or to the left, depending upon the rotation of the sleeve 34. When the sleeve is moved in either direction it carries with it the cross head 24 which oscillates the draw bar, the free end of which is housed within the cross head 25.

I claim:—

1. In a tractor, a draw bar swingably mounted on the tractor, means for positively positioning the free end of the draw bar, said means comprising a screw, a drive shaft spaced from the screw, operative connections between the screw and the shaft whereby rotation of the shaft will cause rotation of the screw, a cross head depending from the screw and having threaded connections with the screw whereby rotation of the screw will cause transverse movement of the cross head, the free end of the draw bar being received by the cross head below the screw.

2. In a tractor, a draw bar swingably mounted on a tractor, a bracket supported by the tractor, bearings carried by the bracket and offset from said bracket, a screw mounted in the bearings, means for causing rotation of the screw, and a U-shaped cross head carried by the screw and for receiving and guiding the free end of the draw bar, said cross head adapted to be moved laterally of the longitudinal axis of the tractor for shifting the free end of the draw bar, an internally threaded sleeve secured to the arms of the U-shaped cross head and engaging the threads of the screw.

3. In a tractor, a draw bar swingably mounted on the tractor, a driver's seat carried by the tractor, a shaft rotatably mounted adjacent the seat, a handwheel causing rotation of the shaft located adjacent the seat, a screw, operative connections between the shaft and screw whereby rotation of the shaft will cause rotation of the screw, a U-shaped cross head depending from the screw and receiving and guiding the free end of the draw bar, operative connections between the cross head and screw whereby rotation of the screw will cause lateral shifting of the cross head and the free end of the draw bar to opposite sides of the longitudinal axis of the tractor.

4. In a tractor, a draw bar swingably mounted on the tractor, brackets supported by the tractor, a screw rotatably mounted in the brackets, a U-shaped cross head supported on the screw, a sleeve having internal threads engaging the threads of the screw, said sleeve being disposed between the arms of the cross head, means on the sleeve and cross head preventing rotation of the sleeve, the free end of the draw bar being received by the U-shaped cross head.

5. In a tractor, a draw bar swingably

mounted on a tractor, a bracket supported by the tractor, bearings carried by the bracket and offset from said bracket, a screw mounted in the bearings, means for causing rotation of the screw, and a U-shaped cross head carried by the screw and receiving and guiding the free end of the draw bar, said cross head adapted to be moved laterally of the longitudinal axis of the tractor for shifting

the free end of the draw bar, an internally threaded sleeve secured to the arms of the U-shaped cross head and engaging the threads of the screw, said cross head being provided with slots, and wings projecting from the sleeve and received by the slots in the cross head to prevent rotation of the sleeve.

VIRGIL L. GIBSON.
